UNITED STATES PATENT OFFICE.

HENRY J. ENNIS, OF WASHINGTON, DISTRICT OF COLUMBIA.

AUTOMATIC VENDING-MACHINE.

SPECIFICATION forming part of Letters Patent No. 371,829, dated October 18, 1887.

Application filed September 16, 1887. Serial No. 249,875. (No model.)

To all whom it may concern:

Be it known that I, HENRY J. ENNIS, a citizen of the United States, residing at Washington, in the District of Columbia, have invented 5 certain new and useful Improvements in Automatic Vending-Machines; and I do declare the following to be a full, clear, and exact description of the invention, such as will enable others skilled in the art to which it appertains to 10 make and use the same, reference being had to the accompanying drawings, and to the letters and figures of reference marked thereon, which form a part of this specification.

My invention relates to that class of machines which is used for selling merchandise—such, for example, as cigarettes or other goods—which may be fed successively to a drawer, from which they may be taken by the purchaser on the deposit of a coin the equivalent in value of the goods, and in which the machine is normally in such a condition that the goods cannot be removed except by the introduction of said coin, which, by reason of its weight and size, operates the mechanism 20 in the machine to unlock a box or drawer, from which a package of the merchandise may be removed.

The novelty consists in the construction, combination, and arrangement of parts, hereinafter more fully described, and pointed out in the claims.

In the accompanying drawings, which illustrate my invention, Figure 1 is a front view, in perspective, of my machine. Fig. 2 is a 35 rear elevation, the back of the machine being removed to show the operation of the parts. Fig. 3 is a side sectional view of the machine on a plane passing in front of the coin duct or channel. Fig. 4 is a horizontal section of the 40 machine on a plane passing over the plane-drawers. Fig. 5 is a detail view showing the device for preventing the introduction of a wire. Fig. 6 is a side view of the same. Fig. 7 is a detail view of part of the mechanism for 45 locking out coins when the supply of the machine is exhausted. Fig. 8 is a detail showing a portion of the coin-guideway and a receptacle for coins of a smaller size than required to unlock the machine. Fig. 9 is a detail of a 50 locking-arm for the sale-drawer. Fig. 10 is a detail showing, in section, one of the sale-drawers and its guide. Fig. 11 is a view of

one of the cutting-knives for severing a cord on an attempt to withdraw a coin. Fig. 12 is a view, in perspective, of the device used to prevent the introduction of the wire. Fig. 13 is a detail view of the locking-out mechanism for coins co-operating with the device shown in Fig. 7.

A suitable frame-work, 1, consisting of a 60 box or housing for the operating mechanism, is provided with a door, 6, by which access may be had to the interior, and with a back, 14, secured by screws. The cash-drawer 7, Fig. 3, is not accessible except when the door 65 6 is open, and is also provided with a lock, the key being carried by an authorized person. Glass panels 22 are set in the front of the frame, on which is inscribed instructions for using the machine. (See Fig. 1.)

The apparatus represented in the drawings is a double one, each side representing a distinct selling apparatus in which the same or distinct kinds or qualities of merchandise may be paid.

33 represent sale-drawers. They are provided with suitable knobs, as shown, and have an open space, 18, of the same size as the cross-section of the reservoir 16 for the merchandise, which is arranged in a vertical column 80 in each reservoir 16. The depth of the drawer 3 is a little greater than the thickness of the article of merchandise or the box or package containing the same. It will be evident therefore that when the drawer is pulled out the 85 lowermost package comes with it, the remaining packages of the column staying in place, and that when the drawer is pulled sufficiently far the package will drop through the open space 18 in the drawer and come to rest on the 90 shelf 4. A block, 20, forming the rear portion of the drawer, prevents the remaining packages from descending until the drawer is restored to its original closed position. It will be understood therefore that by successively opening and closing the drawer the merchandise or packages of merchandise may be withdrawn from the reservoir 16, one at a 95 time, until the supply is exhausted.

As shown in Fig. 4, there are two reservoirs, 100 16 16, formed in the interior front portion of the casing by suitable partitions, 21 22 22. Behind the partitions 22 22 are fixed upon suitable supports secured thereto and to the fixed

part of the casing the guideways 8 9 (see Figs. 2 and 3) for the coins. There are two guideways, 9 9, one for each side of the machine, leading by the channels 8 8 to the exterior openings, 5 5, for the introduction of the coin. At the bend of the channels 8 8, as at 23 23, a slot, 10, is cut in the bottom of the guideway just wide and long enough to retain a coin of the denomination fixed upon as the price of the merchandise, and directly below this slot, in the same vertical line, is placed a trough, 11, one on each side of the machine, so that if anything smaller than the coin of the required denomination is introduced into the exterior opening, 5, it will not follow the guideway, but will fall through the slot 10 into the trough 11. This slot is clearly shown in Fig. 8.

The guideway for the coin is formed of two grooved rails supported at a proper distance apart. At suitable points along each guideway 9 9 are placed a safety device, 12, and a cutting device, 13. Those numbered 12 in the drawings are shaped substantially as those shown in Fig. 12, and are hung from a nearly central eye, 24, upon a pin secured to the side of the guideway, the fulcral point being so placed that the lower or deflecting wing, 25, will normally hang in the path of the coin. The guideway is cut out, as shown in Fig. 5, so as to permit the deflecting-wing 25 and check-wing 26 to swing into the coin's path. The device is made of such a size that the distance between the extreme points of its wings 25 26 is a trifle greater than the diameter of the coin. It will be seen therefore that a coin in sliding under the action of gravity along the guideway will clear wing 26 and will force 25 out of its path, receiving only a slight check to its momentum, but that if a wire or rod be thrust into the guideway the lower wing, 25, will be forced outward, the sharp end of 26 being thrust into the path, firmly locking the wire against further advance and tending to cut or break it.

It has been a comparatively easy matter to "pick" the selling devices heretofore presented to the public, and as they are placed in exposed positions, where the attention of a salesman will not be given, they must, in order to prove at all efficient, be absolutely proof against interference from malicious or unscrupulous persons. The introduction of a wire or a coin bored and secured to a cord have been favored methods of cheating the machine. It will be seen that the check just described will guard against the use of the wire. That shown in Fig. 11 adds an additional guard against the wire, and will also, on any attempt to withdraw a coin by a cord, cut the cord and permit the coin to drop into the receivers 7. This check consists of a knife-blade, 27, to which is secured an eye, 28, by which it is supported at the back of the guideway, the knife-edge normally projecting into the path of the coin and bearing against the plate 50. The coin in its passage along the guideway simply

deflects the knife. If a wire or a cord were attached to the coin, however, once the coin had passed this check, it could not possibly be withdrawn, as the knife would bite into the coin against the plate 10 and cut said cord. It is believed these provisions will prove ample against tampering with the device from the coin-openings, except the method of gorging 75 coins on the unlocking mechanism, which will presently be adverted to.

In order to make a machine of this character safe, it is necessary that the supply-drawer shall not only normally be locked so that it 80 cannot be opened except by the introduction of coin, but also that when once open it cannot be shifted back and forward to extract more than a single package of merchandise. In order to provide for these requirements I 85 have devised mechanism located at the lower portion of the path of travel of the coin, which will be now described.

A latch-tripping dog, 34, is hung from an eye at the side of each guideway, and is so shaped that an arm, 35, will be normally held by gravity in the path of travel of the coin. This dog carries a rod, 36, (shown on a large scale in Fig. 9,) which projects through one of a series of holes drilled in a hinged horizontal latch, 33. This latch is hinged at 37 in a suitable support, 32, so that in its normal position it hangs as shown in Fig. 3. A lug, 61, Fig. 9, bearing against the support 32, prevents the latch 33 from falling too far. Several holes 90 are drilled in this arm, and the rod 36 may be shaped so as to enter any desired hole. The lower side of this latch is provided with a series of teeth, 38 39, and at its extremity with a rectangular recess, 40. To the block 105 20, forming the rear portion of the supply-drawer 3, is firmly secured a lock-bar, 41, cut out to admit the latch 33, part of it overhanging the latch and part passing under the teeth 38 39 and normally engaging one of the same. 110 The overhanging portion prevents the locking-arm from being thrown up sufficiently far to permit the latch-tripping dog 34 to clear the path and allow the coin to drop into the cash-drawer until the sale-drawer has been 115 pulled out sufficiently far to bring the lock-bar beyond the latch. The weight of the coin therefore will hold the latch raised against the overhanging portion of the lock-bar and the teeth on the under side of the latch will be 120 lifted out of engagement with the under side of the lock-bar until the drawer is clear of the detaining influence of the latch. It will be noted that any strain on the latch by a person endeavoring to force open the sale-drawer will 125 be in the direction of its greatest strain, as the strain is a tensile one, and this I regard as an important feature, as the part can be made light and yet of great strength. On the overhanging part of the lock-bar 41 is pivoted a 130 60 deterrent or lug, 42, shaped about as shown in Fig. 2. The face of this lug, which normally rests on the latch, is inclined, as is shown, so that it will permit the latch to be raised by

the weight of the coin until said latch strikes the overhanging part of the lock-bar. (See Figs. 2 and 3.) A check-pin, 55, limits the fall of the lug when it is drawn out clear of the latch, when its lower part drops a sufficient distance to prevent a closure of the drawer, the lower part of the lug engaging the vertical wall of the recess 40. This forms another check to a method of cheating the boxes now in use. For example, let us suppose that a coin of the required denomination were secured to a cord and permitted to fall into the box. It will be remembered that the check heretofore mentioned will permit the string to pass through to the latch-tripping dog 34, but that the coin cannot be withdrawn owing to the cutting action of the knives 13; but once the coin has fallen upon the dog 34 it raises the rod 36 and unlatches the engaging-tooth of latch 33 from the lock-bar 31, so that the drawer can be pulled open. The coin does not fall through till the lock-bar 41 is drawn forward far enough to clear the locking-arm. Ordinarily at this point the coin drops into the cash-box 7; but by holding the cord the latch may be held up so that the drawer might be pushed backward and forward as often as desired and the whole contents of the reservoir 16 removed by the expenditure of a single coin. The lug or detent 42 is designed to prevent this. When the latch is raised and the sale-drawer is drawn forward, as soon as the lock bar 41 reaches the end of the latch the lug 42 drops and the drawer cannot be closed or partially closed until the coin passes the dog 34, because the lower part of the fallen lug 42 now strikes against the wall of the recess 40. The manipulator cannot therefore withdraw his coin or abstract more than a single piece of the merchandise. He is forced therefore either to leave the cord or pull it out, the knife described cutting it if he adopts the latter course. The coin will then drop into the cash-drawer, the dog 34 will resume its normal position, and the free end of the locking-arm 33 will drop sufficiently to clear the lug 42. The drawer can then be closed, the teeth of arm 33 slipping over the lower projection of the lock-bar, and when the drawer is so closed the apparatus is locked and ready to serve a fresh customer.

56, Fig. 2, shows a coin-protecting device. In structure it is similar to those shown at 12. It is placed, however, in such a position that its lower wing will be held out by the coin when the latter rests on the dog 34. Without this check it would be possible, by using coins with beveled edges and slipping them successively in the exterior opening before pulling out the drawer, to gorge the two coins in the guideway at the dog 34, so that when the drawer is pulled they will not lift the dog and unlatch the drawer. In such a contingency a successive opening and closing of the sale-drawer repeatedly would exhaust the entire contents of reservoir 16. Inasmuch, however,

as the first coin will deflect the lower wing of the protecting device 56, the upper wing will be interposed in the guideway, and the second coin cannot pass said wing until the first coin has dropped into the cash-box 7.

We come now to the final feature of the apparatus. In order to deal honorably with its customers, it is necessary that this automatic salesman should announce when its supply of merchandise is exhausted, so that a would-be purchaser may not have his confidence destroyed by depositing a coin and on pulling open the drawer finding that he has no equivalent for his money and pains. I accomplish this desideratum by the following means: On a fixed part of the casing (see Fig. 3) is pivoted a bar, 57, provided with two arms, 43 43, extending across the bottom of the reservoir 16. 75 Each reservoir is provided with a similar rod. Another arm, 44, extends rearwardly and is linked to a connecting-wire, 45, Figs. 2 and 3, which is linked at the top to one arm of a bell-crank lever, 46, Figs. 12 and 13, the other arm 90 of which is pivoted to a bent rod, 47, rigidly secured to a rod, 48. As long as a single package of merchandise remains in the magazine or reservoir, the arms 43 43 are held down and the rod 48 is held clear of the exterior opening, 5; but when the supply is exhausted the weight of the parts or a retractal spring, which is the equivalent, raises the arms 43, operates the bell-crank lever, and thrusts the rod 48 transversely across the exterior opening. This 95 effectively locks out coins, as the rod is located just under the roof of the casing near the coin-opening.

In the lower part of the casing is a sliding drawer, 7, provided at its end with a lock and key, so that a person carrying a key can remove the receipts of the machine.

The forward part of block 20, forming the rear portion of the supply-drawer, is recessed on the bottom, as shown in Fig. 3, so that 105 when the drawer is pulled out the rods 43 can rise, throwing the rod 48 across the coin-opening and locking out all coins as long as the supply-drawer remains open. It is evident, therefore, that if by accident the drawer should 110 be left open a second purchaser cannot introduce his coin until he has first closed the drawer, when the packages of merchandise will fall upon the rods 43 and free the coin-opening.

120 At the outer side of each magazine or reservoir 16, and at its lower part, I place a guide, 60, which holds the lower packages in a proper position to be fed into the sale-drawer.

Having thus described my invention, what I 125 claim, and desire to secure by Letters Patent, is—

1. A vending apparatus comprising a guideway for the coin, a latch-tripping dog extending into said guideway, a knife supported on the guideway, having its cutting-edge downwardly inclined from its pivot, and a bearing on which the knife-edge normally rests.

2. The combination of a slide for withdraw-

ing the merchandise, a piece at a time, a recessed lock-bar carried by said slide, a pivoted latch provided with teeth on its lower face, supported in said recess, said lock-bar being also provided with a pivoted lug adapted to fall in the path of the latch when the latter is out of its normal position.

3. The combination of the coin-guideway, a latch-tripping dog, 34, supported thereon, a latch, 33, adapted to be lifted by said dog when a coin of the required weight rests on said dog, a lock-bar co-operating with said latch, and a slide to which the lock-bar is attached, as set forth.

15 4. The combination of the recessed lock-bar 41, the slide to which it is attached, a fixed support for the lock-bar, said latch being provided with teeth on its under face and a recess at its free end, and a pivoted lug, 42, on the lock-bar adapted to co-operate with the latch to prevent the closure of the slide when the latch is out of its normal position.

5. A bending apparatus comprising a guideway for the coin bent out of a vertical position for a portion of its length and provided in the bend with a trap-slot for smaller coins, reservoir 16, slide 3, lock-bar 41, provided with lug 42, latch 33, and latch-tripping dog 34, as set forth.

30 6. The combination of a slide for withdrawing the merchandise, a lock-bar carried by said slide, a pivoted lug on said bar, a latch parallel to the line of movement of the slide, and a fixed support to which said locking-arm is secured, whereby said slide holds the locking-arm in the line of its greatest strain.

7. The combination of a slide for withdrawing the merchandise, a lock-bar, 41, rigidly secured to the slide, a latch parallel to the line of movement of the slide, a fixed support to 40 which the latch is secured, whereby the slide holds the latch in the line of its greatest strain, and a tripping-dog for releasing said latch, said dog being provided with a projection extending into the path of the coin, whereby, 45 when a coin of the required denomination rests on the projection, the locking-arm will be released from the lock-bar.

8. The combination, with the slide carrying a lock-bar, 41, rigidly secured thereto, of a 50 stationary latch hinged to a rigid support and having teeth adapted to engage the lock-bar, said teeth being located on the arm in the same horizontal plane with the hinge of the arm, as set forth.

9. The combination of a slide for withdrawing the merchandise, a lock-bar carried by said slide, said lock-bar provided with a recess, a hinged latch having a smooth upper face, and a toothed under face extending parallel to the 60 line of movement of the slide, said latch passing through said recess, a latch-tripping dog projecting into the path of the coin, the lock-bar, the latch, and dog co-operating so as to hold the locking mechanism open until the 65 lock-bar is beyond the locking-arm.

In testimony whereof I affix my signature in presence of two witnesses.
